UNITED STATES PATENT OFFICE.

JOHN JOSEPH HIGGINS, OF EAST ORANGE, NEW JERSEY, ASSIGNOR TO WESTINGHOUSE LAMP COMPANY, A CORPORATION OF PENNSYLVANIA.

METHOD OF AND MACHINE FOR MOUNTING FILAMENTS.

Application filed December 2, 1922. Serial No. 604,459.

This invention relates to the manufacture of incandescent electric lamps and more particularly to a machine for mounting filament wire upon the support-wires of a lamp-stem.

An object of the invention is to provide a machine which may be operated to automatically drape a filament onto support wires of a lamp stem.

10 Another object is to provide a machine having coordinating elements which may be operated to positively feed a filament during a mounting operation.

15 An additional object is to provide a machine which may operate to automatically mount a filament of an accurate predetermined length upon support wires of a lamp stem.

20 A further object is to provide a machine which may be adjusted to operate to feed different lengths of filament upon stems for lamps of different wattage and voltage.

25 A still further object of the invention is to provide a machine which may be expeditiously and conveniently operated to mount a filament upon support wires without manual handling of the wire and which may be operated to clamp the filament wire to the leading-in wires of a lamp stem.

30 Other objects and advantages will be apparent as the description proceeds.

The manufacture of incandescent electric lamps includes an operation termed "mounting" which comprises the disposition of a filament wire upon the internal structure of a lamp. It will be understood that an incandescent electric lamp includes a so called stem comprising glass parts, namely a flare tube and an arbor which are fused together and united, leading-in wire being at the same time embedded in the union of the flare and the arbor.

40 In lamps of the tipless type, an additional part termed an exhaust tube is also consolidated with the other glass parts and a communicating passage is provided for the purpose of exhausting through the exhaust tube, after the stem has been sealed into a bulb. After the arbor has been consolidated with a flare tube, support wires are inserted, preferably in suitably spaced enlarged portions or buttons provided on the arbor.

The support wires are disposed radially

and spaced about the circumference of the 55 buttons. Different types of lamps have different numbers of support wires. As an example, a certain type of lamp may have six upper support wires and five lower support wires, each set of wires being staggered with respect to the other. That is, a lower support wire will be positioned in a plane midway between two upper support wires. The ends of the support wires are then provided with either hooks or what 60 65 are known as "pigtails", each consisting of a loop.

The stem, when provided with support wires, is then positioned in a holder and the end of a filament wire is clamped to one 70 of the leading-in wires and then carried over upper and lower supports alternately until it has been properly disposed about the arbor, after which it is secured to the other leading-in wire and severed. When 75 the stem is equipped with a filament it is termed a mount. The operation of mounting a filament as heretofore manually accomplished, was one requiring the exercise of a high grade of skill and the dexterity 80 necessary to properly mount a filament could only be acquired after considerable practice.

Filament wire is extremely fine and of a color which makes it difficult to see and 85 hence difficult to handle. The lack of rigidity of the support members makes it necessary for an operator to be extremely careful not only to properly position the filament but to avoid bending the support wires 90 from their position and thus vary the length of the filament required for a particular stem.

In the manufacture of a volume product, such as an incandescent electric lamp, it is 95 an advantage to avoid all hand operations particularly such operations which require trained operators. The present invention provides a machine which may be actuated to automatically drape a filament about 100 the support wires of a stem. Furthermore, the machine is adapted to operate so as to feed a filament of such length as may be predetermined and governed by an adjustment of certain machine elements.

105 A machine for the above purpose may comprise a rotatable holder for a lamp stem. The holder may be so disposed as to

position a stem with the support members thereof in operative relation to a reciprocable filament-carrier provided with a guide through which a filament may be fed, means being provided to secure the free end of the filament. Means may also be provided for forming hooks upon the leading-in wires and the stem may then be moved to position an end of the filament within the hook 10 of a leading-in wire. Clamping mechanism may then be operated to close the hook and secure the filament. The filament-carrier may then be reciprocated and at the same time the stem holder may be intermittently rotated a given number of degrees 15 with each stroke of the carrier.

During the reciprocation of the carrier, mechanism may operate to positively feed the filament from the guide, thus upon a sufficient number of reciprocations, the stem 20 will have been rotated the required number of degrees and a filament of a given length disposed upon the support wires. The filament may then be clamped to the remaining leading-in wire and severed, whereupon the mount will have been completed and may be removed from the machine.

The foregoing general outline will be more clearly understood from the following description and the accompanying drawings, in which,

Fig. 1 is a front view in elevation of the machine, parts being shown in section;

Fig. 2 is a fragmentary front view in elevation, partly in section and showing, in dot-dash lines, a different position of certain machine elements;

Fig. 3 is a side view in elevation of the machine, partly in section and partly broken away to more clearly show certain features;

Fig. 4 is a transverse view taken on line IV—IV in Fig. 3 and showing a ratchet and pawl mechanism for operating a stem holder;

Fig. 5 is a sectional plan view of a portion of the machine, taken on line V—V in Fig. 1, and showing a device for forming hooks upon the leading-in wires and mechanism for closing the hooks;

Fig. 6 is a view in elevation of a portion of the mechanism shown in Fig. 5 and shows the device for forming the hooks upon the leading-in wires;

Fig. 7 is an enlarged front view of a gripping device for securing the filament wire;

Fig. 8 is a side view of the gripping device shown in Fig. 7 and illustrates the position of a stem with respect to said device;

Fig. 9 is an enlarged detail of mechanism for producing a unidirectional rotary motion of feed rollers during the reciprocation of a filament carrier;

Fig. 10 is another detail of the mechanism shown in Fig. 9 illustrating two positions of certain of the elements for producing the

unidirectional movement of the feed rollers, and showing guide-plates to constrain the lateral movement of the elements;

Fig. 11 is a detail view, partly in section, showing a portion of a stem with a top depression, and a centering tool engaged with the stem.

Fig. 12 is an enlarged end view of one of the pair of clamping jaws illustrated in Fig. 5 and shows an offset cutting edge; 75 and,

Fig. 13 illustrates a stem having a filament mounted thereon.

A machine embodying the present invention may comprise a base plate 15 having uprights or standards 16 and 17 secured thereto. The standards are spaced a suitable distance apart and disposed in a common vertical plane. The standard 16 is provided with brackets 18, 19 and 21 and the standard 17 is provided with brackets 22 and 23. The brackets 19 and 21 are provided with arms 24 and 25, respectively, each of the arms having a slot 26 (see Fig. 5).

At opposite sides of the ends of the arms 24 and 25 are positioned rods 27 and 28. These rods extend from one bracket to the other. Other guide rods 29 and 31 are also secured in the arms 24 and 25 but extend downwardly therefrom and are fastened to an arm 32 of the bracket 18. The four aforementioned guide rods are so disposed as to constitute guides for a reciprocable casting or carrier 33 of rectangular form comprising walls 34, 35, 36 and 37. Secured in the walls 34 and 35 are tubular guide members 38 and 39 respectively. These members project from and extend partway across the interior of the carrier 33 and are adapted to constitute a filament-guide 40 for a filament wire 41, which may be supported on a spool 42 rotatably disposed on a bracket 43 integral with the bracket 19.

Within the carrier 33 is disposed a rocker member 44 pivoted on a trunnion 45 secured in the walls 36 and 37 of the carrier. The rocker member may be of bell-crank form and provided with a relatively short arm 46 and having two relatively long arms 47 and 48 spaced apart and disposed in parallel relation. A feed roller 49 may be rotatable upon the trunnion 45 and disposed between the arms 47 and 48. A second feed or driving roller 51 may be rotatably positioned on a shaft 52, which shaft may be disposed in the slots 54 in the long arms 47 and 48 of the rocker member 44 and in apertures 53 in the sides of the carrier 33.

The roller 51 may be resiliently maintained in contact with the roller 49 through the action of springs 55 secured to the shaft 52 and to suitably extending brackets 56 fastened to the carrier. The filament 41 may be threaded through the filament-guide 40 and between the contacting surfaces of the feed

rollers 49 and 51. The feed rollers may be so disposed that their contacting surfaces lie in a plane coincident with the longitudinal axis of the guide members 38 and 39, the guides being so disposed as to receive a filament and align it when passed therethrough. Thus a movement of the rollers will operate to move or feed filament through the carrier 33. It is obvious that 10 the rollers may be made of any suitable elastic material or material of such character as to provide the necessary frictional engagement with a filament.

The feed roller 51 during the reciprocation of the carrier is driven by providing the shaft 52 with a loose pinion 57 secured to the feed roller 51 and adapted to be moved when the pivoted member 44 is oscillated into mesh with the teeth of one of the 20 racks 58 and 59. The racks may be disposed at opposite sides of the pinion 57, suitably spaced therefrom and secured to the arms 24 and 25 of the brackets 19 and 21. An alternate engagement of the pinion 25 57 with the racks results in a rotation of the feed rollers 49 and 51 in one direction during the up and down movements of the carrier 33. Thus, if upon an upward movement of the carrier, the pinion engages with 30 the rack 58, it will be rotated in the direction indicated by the arrow in Fig. 1. Upon the downward movement of the carrier when the pinion is engaged with the rack 59, the rotation of the pinion will be in the same direction. It will be evident that by 35 reason of this movement, a unidirectional feed will be imparted to the filament 41.

Mechanism for producing the above actuation of the pinion 57 may comprise a link 40 61 pivoted to the arm 46 by a pin 62 and to an arm 63 of a reciprocable guide 64 by a pin 65. The guide 64 may be slidable upon the lower sections of the guide rods 29 and 31.

45 Motion is transmitted to the guide 64 through a connecting rod 66 which is pivoted on a stud 67 fastened in a friction plate 68 which plate is disposed in lateral grooves 69 of a slot 71 radially positioned in rotatable member of disc 72. The friction plate 68 may be secured at various points along the radial slot to give a variation in the stroke or cycle of movement of the connecting rod 66.

55 The disc 72 may be secured to a shaft 73 journaled in bearings 74 and 75 (Fig. 3), and an actuation of the shaft may be had by a manual rotation of a hand wheel 76 or by means of a suitable belt connected 60 with a sheave 77 and a source of energy (not shown). The handle or grip 80 may be removed by unscrewing. By reason of the connecting rod 66, the guide 64 is reciprocated and consequently translates similar motion to the carrier 33 by reason of the 65

link 61. Upon the up stroke of the connecting rod 66, the link 61 imparts an upward thrust to the end of the arm 46 thus rocking the rocker member 44 and causing the teeth of the pinion 57 to engage with the rack 58. 70

After the disc 72 has rotated until the stud 67 of the connecting rod has moved past its upward dead center position, a reverse movement or stroke of the connecting rod will result, effecting a downward pull 75 upon the link 61. The rocker member 44 will then be moved about the pin 45 carrying the pinion 57 into engagement with the teeth of the rack 59. For the purpose of preventing an engagement of the pinion 80 and rack until the carrier 33 is in a predetermined position, a pair of guide plates 78 and 79 are disposed at opposite sides and adjacent to the carrier. These guide plates are positioned in parallel relation 85 and are secured to brackets 19 and 21 by means of tap bolts 81 which extend through slots 82 in the plates thereby permitting their vertical adjustment. The plates 78 and 79 are so disposed that an edge of each 90 is spaced a sufficient distance apart to permit a vertical movement of the shaft 52 which extends from the carrier 33 on both sides and between the guide plates.

As illustrated in Figs. 1 and 10, the shaft 95 52 is removed from the surface 83 of an edge of plate 79 during the upward movement of the carrier, however, upon a reverse movement of the link 61, the rocker member 44 is actuated and the pinion 57 is urged 10 toward the rack 59, but surface 83 is so positioned as to make contact with the shaft 52 and to prevent the engagement of the rack and pinion until a downward movement of the carrier has caused the shaft 10 52 to traverse the surface 83 and make contact with a surface 84 disposed in a plane in sufficiently near relation to the rack 59 to permit the pinion 57 to engage with the teeth of the rack. During the downward 11 movement, the pinion will be rotated in the direction of the arrow as indicated and upon the return or upward movement of the link 61, the rotation of the pinion 57 will be continued in the same direction for a portion of the stroke by the effect of similar but oppositely disposed surfaces 85 and 86 of the guide plate 78.

After the filament has been threaded through the member 38 of the filament-guide 12 40, it is passed between the feed rollers and through the other member 39 and thence may be led downwardly and gripped between a pair of jaws 91 and 92, the operation of which will be presently described.

12 A stem, 93 which may comprise a flare tube 94, arbor 95, exhaust tube 96, leading in wires 97 and 97' and the usual support wires 100 inserted in the upper and lower buttons of the arbor, may be supported be-

tween upper and lower centering members or pins 98 and 99 respectively. The upper pin 98 may consist of a pointed member having threads 101 and may be screwed vertically through an end of arm 102 of the bracket 28. The pin may therefore be adjusted vertically and may be held in a fixed position by a lock nut 103. The pointed end of the centering pin 98 is adapted to enter a recess in the upper surface of the top button of the stem (see Fig. 11). A machine for producing stems with a recess is described and claimed in the copending application of Madden and Higgins, Serial No. 565,126, filed June 1, 1922, lamp making machinery and articles produced thereby (W L 162) and assigned to the Westinghouse Lamp Company.

The lower centering member 99 is provided with a center point 104, over which the lower end of the exhaust tube 96 may be disposed. It will be obvious that although the centering pins are shown provided with pointed ends, other means may be employed to secure the stem as, for instance, an end of the centering pin 99 may be provided with a socket to fit the end of the exhaust tube. A similar arrangement may be employed for holding the upper end of the stem.

In addition to the centering pins for supporting a stem, jaws 105 and 106 are provided at the end of bell crank members 107 and 108, respectively. These members are pivoted on pins 109 secured in bearings of a thimble or sleeve 111. The jaws are normally urged toward each other or to their closed position through the action of springs 112 disposed between projections 113 of the sleeve 111 and arms 114 of the bell cranks 107 and 108.

For the purpose of positioning a stem between the centering members, the lower member 99 is adapted to be moved downwardly with the sleeve 111 and is secured to the sleeve by a pin 115. The sleeve is slidably disposed upon a hollow shaft 116 that extends through a hub 117 at the end of an arm 118 of the bracket 22. This shaft is provided with an integral collar 119 and between the collar and the upper surface of the hub 117 is disposed an anti-friction member 121, which may comprise the usual form of bearing as, for instance, a plurality of balls in a ballrace.

The shaft 116 may extend below the hub 117 and have secured thereto a ratchet wheel 122, the shaft being thus prevented from vertical movement. The ratchet wheel may be intermittently rotated to rotate the shaft and consequently the stem secured by the jaws 105 and 106. Mechanism for performing this operation will be presently described.

For the purpose of maintaining the sleeve

111 and consequently the centering member 99 in an upper normal position the shaft 116 is provided with a recess 123 and a spring 124 is positioned about the member 99 and between an annular interiorly projecting shoulder 125 of the sleeve 111 and an end of the recess 123. Thus the spring 124 may act to normally urge the gripping mechanism and the centering member 99 upwardly. As an operator presses downwardly upon the lever arms 114 of the jaws to open them, the centering member 99 also moves downwardly, thus permitting the positioning of a stem. A release of the lever arms permits the return of the member 99 to center the stem and simultaneously results in a closure of the jaws 105 and 106, to grip the stem and prevent its rotation with respect to the holder 108. For the purpose of preventing relative rotation of the sleeve 111, a guide rod 126 may be secured in the upper surface of the collar 119 and disposed in an aperture 127 provided in the sleeve 111, the sleeve being thus movable vertically with respect to the rod 126.

The intermittent rotation of a stem secured by the jaws 105 and 106, is accomplished through the action of the disc 72 which is provided with two cam surfaces or projections 128 and 129 disposed at the periphery of the disc 72 and in substantially diametrically opposite relation. As the disc is rotated, the projections may alternately engage with a roller 131 disposed at the end of a slide rod 132 positioned in a bearing 133. The opposite end of the slide-rod may be integral with or suitably secured to a pull-rod 134 having an end thereof disposed in operable relation to the ratchet wheel 122. Springs 135 and 136 are secured to the pull rod and to the bearing 133 to normally urge the roller 131 toward the disc 72 and in the path of the projections 128 and 129.

An end of the pull rod, adjacent to the ratchet wheel, is provided with a pawl 137 (see Fig. 4), disposed in a casing 138 in the usual manner. A guide 141 is provided to afford a bearing for a horizontal portion of the pull rod 134.

When the disc 72 rotates 180°, the projection 129 will engage with the roller 131 and cause an actuation of the ratchet wheel and a rotation of the stem a number of degrees depending upon the movement required, as for instance, if the upper button of the stem is provided with six support wires and the lower button with five, the ratchet wheel may have twelve teeth thus causing a rotation of the stem a distance equal to half the distance between the upper support wires.

It will be appreciated that when the next actuation of the ratchet wheel occurs, the filament carrier will have been moved to the

limit of its movements in one direction. For the purpose of eliminating the undesired effect of lost motion and preventing the stem holder from rotating too freely, a 5 brake member comprising a flat spring 142 may be secured to the arm 118 and positioned with its free end in tensional engagement with the collar 119 of the shaft 116.

A filament having been threaded through 10 the filament guide 40 may be gripped by the jaws 91 and 92 (see Figs. 7 and 8) which are disposed on studs 143 and 144 respectively, integral with an oscillatory member 145. The latter is pivoted on a pin 146 15 in a bearing 147 secured to the end of the arm 24 of the bracket 19. The jaws may be integral with hubs 148 and 149 having pinions 151 and 152 respectively pinned thereto, the pinions being so disposed as to 20 mesh together. An opposite movement or opening of the jaws may be caused by a movement downwardly of a lever arm 153, which arm may be integral with one of the hubs of the jaws, for instance, the hub 149.

25 A spring 154 having its ends secured to the arms of the jaws 91 and 92, serves to maintain the jaws normally closed. The jaws may, however, be secured in an open position by a latch 155, which is carried 30 on an arm 156, secured to the oscillatory member 145. A stop 157 is provided to limit the movement of the latch 155 in one direction, a spring 158 being provided to maintain the latch in contact with the stop. 35 When the lever arm 153 is moved to open the jaws and the end of the arm passes a lip 159 of the latch, the jaws are held open and may be released upon a downward movement of the latch.

40 It will be appreciated that by reason of the oscillatory member 145, the jaws are movable in a plane transverse to that in which they move when opening and closing. Thus when the portion 39 of the filament 45 guide is positioned as shown in Fig. 8, and the filament is gripped by the jaws, the end of the filament-guide will be disposed beneath a beveled edge 160 of the jaws. The filament guide may, however, be moved upwardly and by reason of the oscillatory member 145 to which the jaws 91 and 92 are attached, the jaws will permit the passage of the guide as it is moved and makes contact with the beveled surface 160.

50 The jaws 91 and 92 may be returned to their normal position by a spring 161, secured to the oscillatory member 145 and to a suitable bracket 162, and a set screw 163' may be provided to limit the upward movement of the member 145. The jaws 91 and 92 may grip the filament and hold it in position until a leading-in wire is so disposed that the filament is positioned within the hook thereof.

55 Hooks may be provided in the leading-in

wires of the stem prior to the positioning of the stem for mounting, however, the present invention provides mechanism for forming a double loop or bend at the end of the wire, by a device which may constitute a part of the present machine. The double bend is provided so that a filament may enter into a loop on either side of the leading-in wire. Mechanism for producing this double bend may consist of a 70 member 161 (see Figs. 1 and 5) slidably disposed upon the standard 17 and maintained from movement about the standard by a feather 162. Collars 163 and 164 provided with set screws may be adjustable 75 upon the standard 17 to limit the vertical movement of the slidable member 161.

The member 161 is provided with oppositely disposed extensions 165 and 166, the longer extension 166, having recesses 167 which may comprise the female portions of dies for bending wires. Male portions of the dies may consist of ribs 169 and the end or pins 171. The male portions may be carried at the end of arms 172, the arms being pivoted upon a pin 173 secured in the extension 165, and provided with handles 174 pivoted on pins 175, the handles being normally maintained against stops 176 through the action of relatively strong springs 177 which may be secured to the handles 174 and to the arms 172.

The pins 171 may be operated by levers 178 which are adapted to make contact with the pins and are pivoted on tapbolts 179 secured in the arms 172 and connected to the handles 174 by links 181. Thus the handles 174 may be gripped to move the arms to bring the male members 169 into the female portions of the dies thereby bending one loop in the wire. Springs 182 normally maintain the pins or male members 171 from engagement with the wire during this first loop forming operation, the springs 177 offering sufficient tensional opposition to 100 permit the forming of this first bend without causing any actuation of the levers 178. However, when one loop is formed, a continued pressure upon the handles 174 serves to overcome the opposition of the springs 177 causing the levers 178 to make effective contact with the pins 171 and thus thrust the ends thereof into the female portions 168 of the die with the result that a second loop is formed in the wire. This loop forming 110 device may be moved to position to form the loops but may be removed after the loops are formed to a lower position as, for instance, that indicated in dot-dash lines in Fig. 1. For the purpose of frictionally maintaining the loop forming device in a given position, a tension member such as the spring 183 may be provided, one end being secured to a collar integral with the

115 lower side of the slidable member 161, the 120 125 130

free end of the spring being in tensional engagement with the standard 17.

The advantage of providing the leading-in wires with a double loop will be apparent 5 from the fact that by means thereof, the stem may be rotated either in a clockwise or a counter-clockwise direction to position a filament in a loop on either side of the leading-in wire. Double loop wires are, in the 10 present construction, desirable inasmuch as the leading-in wire 97 is positioned by a movement of the stem in the direction of the arrow "X", (Fig. 5) whereas during the mounting operation, the stem is intermittently rotated in the direction of the arrow "Y" and the leading-in wire 97' is moved to bring it on the opposite side of the filament for clamping. The above operations will be more fully described below. 15

20 After the loops have been formed in the wire, the stem may be rotated by turning about its vertical axis, causing the exhaust tube to rotate between the jaws 105 and 106. It will be understood that these jaws 25 grip the stem sufficiently to cause it to rotate with the holder, but that the stem may be manually rotated between the centering members 98 and 99. A leading-in wire may be disposed with the loop thereof about the 30 filament and the loop may then be closed to grip the filament. For this purpose, a pair of clamping devices 184 and 185 (see Fig. 5) each comprising a pair of jaws 186 and 187, may be provided at the end of rocker arms 35 188, pivoted in bearings 189 which may be secured to the guide plates 79, and properly located with respect to the leading-in wires 97 and 97' of the stem.

The clamping devices 184 and 185 may be 40 moved to or from their operative positions and, as shown in Fig. 5, one device may be in position for closing or clamping a loop and the other device in its outer position. Springs 190, secured to the bearings 189 and 45 to the rocker arms 188, serve to normally maintain the arms in their outer positions. Set screws 191 may be provided to afford a variation in the limited movement of the arms in one direction.

50 When a device, for instance, the clamp 185, is positioned, as illustrated, to close a loop, the shank of the jaw 187 may be actuated to operate the jaw and the loop will thus be closed upon the filament. This first 55 operation of closing a loop may be performed prior to the actuation of the filament carrier 33 for the mounting operation. However, upon the completion of the mounting and when the filament is positioned in 60 the second or last leading-in wire, it is desirable to sever the wire as it is clamped about the filament.

For this purpose one of the clamping devices, for example 184, may be provided 65 with a cutter such, for instance, as that

shown in Fig. 12 in which a projection 194 on jaw 186 is provided which, together with edge 195 on jaw 187, constitute shearing edges so that when the jaws close and the leading-in wire is clamped about the filament, the cutting edges will operate to sever the filament.

Having described the various machine elements for performing the several operations required to mount a filament upon the support wires, a description of operation of the device as practiced will be given.

A stem as received from the stem making machine may be provided with a given number of support wires. As an example, a stem having six upper and five lower support wires may be considered. It is to be understood that the lamp part referred to as a stem or lamp stem, includes the aforementioned component parts namely the several consolidated glass parts, leading-in wires or conductors and the support wires. The leading-in wires of a stem as employed in the present invention are straight, no hook having been formed thereon. The operator presses down upon the levers 107 and 108, thereby opening the jaws 105 and 106 of the stemholder and separating the centering members 98 and 99 sufficiently to permit the disposition of a stem therebetween. A release of the levers causes a return of the lower centering member and the stem is thus centered and simultaneously gripped by the gripping jaws.

A stem having thus been positioned in the stem holder, the free end of a filament may be secured between the jaws 91 and 92. The slideable member 161 which carries the jaws for forming the double loops upon the leading-in wires may then be positioned so that the ends of the leading-in wires are in operative relation to the double-loop forming dies. The handles 174 may then be operated to move the male dies 169 on the arms 172, and to operate the pins 182 thereby forming double loops in the wires. The loops having been formed, the slideable member and die carrier 161 may be lowered and positioned upon the collar 163. The stem may then be manually rotated in the direction of the arrow "X" (see Fig. 5) until the leading-in wire 97 is so disposed that the filament will be positioned in one of the loops.

It may be assumed that the filament carrier 33 is at this stage of the operations, in its upper position and the clamping devices 184 and 185 are in their outer positions with respect to the filament. The clamping device 185 may then be moved to its operative position with respect to the loop disposed about the filament and the jaws of the clamping device disposed upon the opposite sides of the relatively straight portions of the loop as shown in Fig. 5. The jaws may

be actuated and the leading-in wire clamped to the filament after which the gripping jaws 91 and 92 may be opened and so retained by the latch 155. Suitable motion being then imparted to the shaft 73, the disc 72 may be rotated in the direction of the arrow "Z", as indicated in Fig. 1, the carrier reciprocated, and the stem intermittently rotated, through their association with the disc 72.

As the filament carrier moves from the hook of one support member to another, the filament is fed by means of the feed rollers 57 and 49. It will readily be seen, that by varying the relative position of the surfaces 85, 86 and 83, 84 the filament may be fed during given portions of the travel of the carrier 33. Thus the filament may be positively fed from above an upper support member to a given distance below a lower support member or the feeding operation may be performed during the movement of the filament guide between the supports.

The cam portions 128 or 129 of the disc 72 may be so positioned as to operate the pull rod 134 when the filament guide is above or below a support-member thus causing a rotation of the stem a given number of degrees. Therefore, with each stroke of the connecting rod 66 the filament is carried over a support-member and as the machine is operated, a filament is mounted or draped over the support wires.

When the filament has been mounted upon the hooked support members and the filament carrier 33 is in its lower position, as indicated in dotted lines in Fig. 2, the filament wire will be in position adjacent to the leading-in wire 97 and the filament guide 39 may be moved down to below the gripping faces of jaws 91 and 92 to a position as indicated in dotted lines in Fig. 1. The gripping jaws may then be closed to grip the end of the filament wire and the clamping device 184 operated to clamp the leading-in wire about the filament and to sever the filament, thereby completing a mount which may then be removed. The filament wire will be secured in the gripping jaws 91 and 92 and the filament carrier may be moved to its upper position. The filament guide 39 of the filament carrier passes the gripping jaws 91 and 92 by reason of their pivoted connection with the bearing 147. The end of the filament will, however, remain secured between the gripping jaws to hold it during the positioning of another leading-in wire and another section of filament may be mounted.

It will be evident that with the present machine, a filament may be automatically draped about the support wires of a lamp stem and that this operation may be performed with accuracy and dispatch, avoiding any pull or strain upon the support wires

because of the positive feed imparted to the filament wire during the mounting operation.

Although I have shown and described a preferred embodiment of my invention, it is to be understood that many modifications may be made therein without departing from the spirit and scope of the appended claims.

What is claimed is:

1. A filament mounting machine comprising a lamp stem holder, rotatable members for positively feeding a filament and means for causing a relative movement of said feeding means and said stem. 75

2. A filament mounting machine comprising a lamp stem holder, rollers for engaging and positively feeding a filament longitudinally and means for causing a relative movement of said feeding means and said stem during the longitudinal movement of 85 said filament.

3. A filament mounting machine comprising a lamp stem holder, a filament guide, means for changing the relative positions of said stem and said guide and means for positively moving a filament through said guide during said relative movement. 90

4. A filament mounting machine comprising a stem holder, a filament guide, means for reciprocating said guide to mount a filament upon support wires of a stem positioned in said holder and means for positively feeding a filament through said guide during the reciprocation thereof. 95

5. A filament mounting machine comprising a stem holder, a filament guide, means for reciprocating said guide, means for intermittently rotating said stem holder during the reciprocation of said guide and means for positively moving a filament through 100 said guide during the reciprocation thereof.

6. A filament mounting machine comprising a lamp stem holder, a filament guide, means for reciprocating said guide to mount a filament upon a stem supported in said holder and means for causing a positive movement of a filament through said guide during a portion of its reciprocatory movement. 105

7. A filament mounting machine comprising a lamp stem holder, a filament guide, means for causing a reciprocation of said guide transversely to its axis to mount a filament upon support wires of a stem secured in said holder and means for causing a positive movement of a filament through said guide during the reciprocatory movements thereof. 115

8. A filament mounting machine comprising a stem holder, a filament guide, means for reciprocating said guide to mount a filament upon support wires of a stem supported in said holder and means for positively feed- 125

ing a filament from the guide during the passage of the guide from one support wire to another.

9. A filament mounting machine comprising means for holding a stem, a filament guide, means for reciprocating said guide to mount a filament wire upon support wires of a stem secured in said holder, means for positively feeding the filament from the 10 guide during the movement of said guide between the support wires and means for changing the relative positions of said support wires and said guide to cause the filament wire to pass between said support 15 wires.

10. A filament mounting machine comprising a lamp stem holder, rotatable members for positively feeding a filament, means for reciprocating said feeding means to mount a 20 filament upon support wires of a stem and means for intermittently rotating said stem during the reciprocative movement of said feeding means.

11. A filament mounting machine comprising means for holding a lamp stem, a filament guide, means for reciprocating said guide and adjustable means for feeding a filament axially through said guide during movement thereof.

12. A filament mounting machine comprising a lamp stem holder, a filament guide, means for reciprocating said guide, means for feeding a predetermined amount of filament through said guide during each movement thereof and means for varying the amount of filament fed through said guide during each movement.

13. A filament mounting machine comprising a lamp stem holder, a filament guide, means for reciprocating said guide, means for feeding filament through said guide during a portion of each movement thereof and means for terminating the feeding of said filament through said guide during a 45 portion of the movement of said guide.

14. A filament mounting machine comprising means for holding a lamp stem, a filament guide, means for reciprocating said guide, means for feeding a predetermined 50 amount of filament through said guide during each movement thereof and means for regulating the amount of filament moved through said guide during the reciprocation thereof.

15. A filament mounting machine comprising means for holding a lamp stem, means for forming hooks at the ends of leading-in wires of said stem, means for positioning a filament, means for clamping said filament in the hook of one of said leading-in wires, means for draping said filament over support members of said stem and means for clamping said filament in the remaining leading-in wire.

16. A filament mounting machine com-

prising a rotatable stem holder, a filament guide, means for reciprocating said guide, means for causing a movement of a filament independently of the movement of said guide, means for intermittently rotating said stem holder in a given direction with each movement of said guide, and means for varying the amount of filament fed through said guide during each of said movements.

17. A filament mounting machine comprising means for holding a lamp stem having leading-in wires projecting therefrom, means for forming loops in said wires, means for clamping a filament wire 80 to said loops and means for mounting said filament upon support wires of said stem.

18. A filament mounting machine comprising a stem holder, means for forming hooks in the leading-in wires of a stem 85 supported in said holder, means for positively feeding a filament and means for causing a relative movement of said feeding means and said stem.

19. A filament mounting machine comprising a stem holder, means for forming hooks in leading-in wires in a stem positioned in said holder, means for positively feeding a filament, means for causing a relative movement of said feeding means and 90 said stem holder to mount the filament on support wires of said stem and means for clamping said filament in the hooks of said leading-in wires.

20. A filament mounting machine comprising a filament guide carrier provided with feed rollers, a pinion secured to one of said rollers to provide driving means therefor, means for reciprocating said carrier, racks disposed at opposite sides of said 105 pinion, an oscillatory member associated with said pinion and means for engaging said pinion with one of said racks during the reciprocation of said carrier.

21. A filament mounting machine comprising a filament guide carrier provided with feed rollers, a pinion secured to one of said rollers to provide driving means therefor, means for reciprocating said carrier, racks disposed at opposite sides of said pinion, an oscillatory member associated with said pinion, means for engaging said pinion with one of said racks during the reciprocation of said carrier, said carrier reciprocating means comprising a rotary member 110 having a link connection with said carrier and means associated with said member for effecting an intermittent rotation of said stem holder during the reciprocation of said carrier.

In testimony whereof, I have hereunto subscribed my name this 1st day of December 1922.

JOHN JOSEPH HIGGINS.
